UNITED STATES PATENT OFFICE.

WILLIAM E. HILL, OF KALAMAZOO, MICHIGAN.

LOG-SPLITTER.

SPECIFICATION forming part of Letters Patent No. 508,221, dated November 7, 1893.

Application filed December 1, 1892. Serial No. 453,704. (No model.)

To all whom it may concern:

Be it known that I, WILLIAM E. HILL, a citizen of the United States, residing at Kalamazoo, county of Kalamazoo, State of Michigan, have invented a new and useful Log-Splitter, of which the following is a specification.

The object of this invention is to construct a steam splitting machine for splitting logs, to consist essentially of a steam cylinder with a splitting ax attached to one end of the piston rod and to be operated by the end thrust of said piston.

Another object is to combine the steam cylinder, piston rod and ax with a rope and toggle tongs in such a manner that when the piston rod ascends the ax will be raised and the log be raised up to be mounted upon the splitting block, at the same time.

Further objects will appear in the detailed description.

In the drawings forming a part of this specification, Figure 1 is an elevation showing the machine as when located over a stream of water; Fig. 2 an enlarged perspective view of the ax; Fig. 3 an enlarged view of lettered details at the top of Fig. 1; and Fig. 4 is a vertical section on line 4-4, in Fig. 3, looking from a point at the right.

As here shown, the machine is mounted on abutments over a stream, so that the logs, J, may be elevated out of the water and after being split the bolts fall into the water and float away, as illustrated at M and N.

At A is illustrated a frame-work upon which the machine is mounted, parts of said frame-work being broken away to show the construction and arrangements of the machine proper. The log, J, after being elevated, is placed upon the splitting block, K, mounted upon a central abutment, L or any other suitable foundation.

B is the steam cylinder, rigidly attached to the upper beams of the frame-work, as shown in Fig. 1. This steam cylinder has a piston rod, both ends of which extend out of the ends of the cylinder. To the lower end of said piston rod is attached the ax, D. This ax may consist of a single blade, so as to split the log in halves, or it may consist of four radiating branches at right angles to each other, as shown in Fig. 2, so as to split the log in quar-

ters. From this it will be seen that the ax itself may be in any suitable shape desired.

To the upper end of the piston rod, C, is 55 swivelly attached a pulley, E, pivotally mounted in a swiveled head, F.

Fig. 4 clearly illustrates how the pulley block is swiveled to the upper end of the piston rod, C, the upper end of said piston rod 60 being provided with a peripheral groove, a, and a pin, e, being inserted through the pulley block in said groove.

A rope, chain or cable, G, is fastened at its lower end to some fixed support and from thence passed up over the pulley, E, and extends downward, to the lower end of which are attached toggle tongs, I. To keep this cable or rope from contact with the steam cylinder, it is passed between two rollers, n n, pivotally 70 attached to a beam of the frame-work, as in Fig. 1.

At H is shown a lever, which is attached to the throttle of the steam cylinder in the ordinary manner, so that steam may be admitted to either end of the cylinder, B, to throw the piston rod up or down, as desired. At each end of the cylinder is a rubber cushion, x x, which may be employed to cushion the shock, during the action of the piston rod. 80

In the operation, steam is admitted into the upper end of the cylinder, which of course will lower the ax, forcing it through the log and allowing the bolts to fall into the water. During this action the toggle tongs also lower, 85 from the fact that the pulley is carried down with the piston rod. The tongs are then attached to another log in the stream and steam admitted into the lower end of the cylinder, which will cause the piston rod to rise, 90 raising the ax and the tongs, with the log, at the same time. The log is then mounted upon the splitting block by a person in attendance, standing on the platform, P, who also operates the throttle lever H and detaches the tongs, and the first operation is then repeated. During this action the ax is permitted to follow the natural course of the grain through the log, from the fact that the swivel at the upper end of the piston rod 100 allows said piston rod and the ax to turn, which would be desirable in case the grain of the log is winding.

Referring again to Fig. 2, it will be ob-

served that the ax is provided at the center with a projecting point, *i*, which centers in the log and forms a sort of axis for the log to turn upon, but this may be employed or not.

5 This machine of course may be employed in any location, whether over a stream or not. It may be employed for splitting stave or heading bolts or even for splitting up short logs into fuel, but of course one of the principal ideas is to make it convenient for handling heavy logs which are floated down a stream, for first sawing the logs into proper lengths and then splitting them into the proper sized bolts, which can be more conveniently handled.

Having thus described my invention, what I claim as new, and desire to secure by Letters Patent of the United States, is—

1. A steam splitting machine, comprising a steam cylinder, a piston rod therein, both ends of which extend out of the ends of the steam cylinder, the lower end of said piston rod having attached thereto an ax, the upper end of said piston rod bearing a pulley, a rope, chain or cable passed over said pulley, and log tongs attached to the lower end of said rope, chain or cable, whereby the ax and log are raised at the same time; substantially as set forth.
2. In a log splitting machine, the combination of a suitable frame, a steam cylinder supported by said frame, a piston rod, both ends of which extend out of the ends of the steam cylinder, one end of said piston rod having attached thereto an ax, the other end having attached thereto a swiveled pulley, and a rope, chain or cable rigidly attached to some suitable support at one end and passed over

the pulley, and log tongs attached to the free end of said rope, chain or cable; substantially as set forth.

3. In a log splitting machine, the combination of a suitable frame, a steam cylinder supported by said frame, a piston rod, both ends of which extend out of the ends of the steam cylinder, one end of said piston rod having attached thereto an ax, the other end having attached thereto a swiveled pulley, and a rope, chain or cable rigidly attached to some suitable support at one end and passed over the pulley, log tongs attached to the free end of said rope, chain or cable, and frictional guide-rollers between which said rope, chain or cable passes.

4. The combination of a suitable frame-work mounted over a body of water, a steam cylinder supported by said frame-work, a piston rod having both ends passed out of the ends of the steam cylinder, an ax attached to the lower end of the piston rod, a swiveled pulley attached to the upper end of the piston rod, a rope, chain or cable rigidly attached at one end, from thence being passed up over the pulley and extending downward, log tongs attached to the lower free end of said rope, chain or cable, an abutment in the water and a suitable splitting-block mounted upon said abutment; substantially as set forth.

In testimony to the foregoing I have hereunto subscribed my name in the presence of two witnesses.

WM. E. HILL.
